UNITED STATES PATENT OFFICE

GEORGE E. GLATTHAR, OF UNIVERSITY HEIGHTS, AND FREDERICK WENING, OF SOUTH EUCLID, OHIO

DESIGN FOR A LIGHTING FIXTURE

Application filed December 3, 1932. Serial No. 46,305. Term of patent 7 years.

To all whom it may concern:

Be it known that we, GEORGE E. GLATTHAR and FREDERICK WENING, citizens of the United States, and respectively residing at University Heights and South Euclid, in the county of Cuyahoga and State of Ohio, have invented a new, original, and ornamental Design for Lighting Fixtures, of which the following is a specification, reference being had to the accompanying drawing, forming a part thereof.

The figure is a side elevation of a lighting fixture showing our new design.

The canopy, socket housing and the three flaring reflector members are all circular in cross section and the pendant ornament at the lower end of the lowermost reflector member is of generally spherical shape.

We claim:

The ornamental design for a lighting fixture, as shown and described.

GEORGE E. GLATTHAR.
FREDERICK WENING.
